UNITED STATES PATENT OFFICE.

LOUIS F. TRINCHARD, OF NEW ORLEANS, LOUISIANA.

DESIGN FOR A CORN-HOLDER.

SPECIFICATION forming part of Design No. 35,699, dated February 4, 1902.

Application filed October 7, 1901. Serial No. 77,927. Term of patent 7 years.

To all whom it may concern:

Be it known that I, LOUIS F. TRINCHARD, a citizen of the United States, residing at No. 2605 Baronne street, city of New Orleans, parish of Orleans, and State of Louisiana, have invented and produced a new and original Design for a Corn-Holder, of which the following is a specification, reference being had to the accompanying drawing, forming part thereof.

The accompanying drawing is a view of a corn-holder, showing my new design.

As shown in the drawing, the leading or material feature of my design consists of a U-shaped implement having two members or arms and twists or turns A and B, disposed or arranged as shown in the drawing, one of the members or arms describing an

oblong leaf shape, with two extending pointed horn-like prongs, and the other member or arm describing a similar outline, with like extending prongs, having additional turns or loops C, as likewise shown in the drawing.

Having described my invention, what I claim as new, and desire to secure by Letters Patent, is—

The design for a corn-holder, as herein shown and described.

In testimony whereof I have signed my name to this specification in the presence of two subscribing witnesses.

LOUIS F. TRINCHARD.
